DESIGN FOR A DOOR PULL

Earl M. Borchers, Rockford, Ill., assignor to
American Cabinet Hardware Corporation,
Rockford, Illinois, Rockford, Ill., a corporation
of Illinois

Application August 8, 1945, Serial No. 121,314

Term of patent 7 years

(Cl. D10—8)

To all whom it may concern:

Be it known that I, Earl M. Borchers, a citizen
of the United States, residing at Rockford, in
the county of Winnebago and State of Illinois,
have invented a new, original, and ornamental
Design for a Door Pull, of which the following
is a specification, reference being had to the accompanying
drawing, forming a part thereof.

Figure 1 is a side elevational view of the door
pull embodying my new design.

Figs. 2 and 3 are respectively front and end
elevational views of the same.

The dominant features of the design reside in
the portion shown in full lines in the drawing.

I claim:

The ornamental design for a door pull, substantially
as shown and described.

EARL M. BORCHERS.
